PRESSING MACHINE CLAMP

Hyman Elias Cohen, Brooklyn, N. Y., assignor to
New York Pressing Iron Co. Inc., New York,
N. Y., a corporation of New York

Application January 2, 1937, Serial No. 118,835

2 Claims. (Cl. 38—12)

This invention relates to a new and improved pressing machine.

One of the objects of the invention is to provide an improved pressing machine for pressing shirts and other garments which have tail portions which must be held in position during the pressing operation.

Another object of the invention is to provide an extremely simple and convenient device for holding a tail portion of the shirt or other garment, in position, while the shirt or other garment is being pressed.

Another object of the invention is to provide a pressing machine having a device of this type, in which said device is extremely accessible and will not interfere with the access to the machine when the attachment is moved to the inoperative position.

Other objects of the invention will be set forth in the following description and drawings which illustrate a preferred embodiment thereof, it being understood that the above statement of the objects of the invention is intended generally to explain the same without limiting it in any manner.

Fig. 1 is a front elevation of the improved machine.

Fig. 2 is a sectional view, partially in elevation, on the line 2—2 of Fig. 1.

Fig. 3 is a side elevation on the line 3—3 of Fig. 1.

Fig. 4 is an enlarged sectional view, partially in elevation, on the line 4—4 of Fig. 3.

It has been known for many years to provide machines for pressing shirts or the like, in which a device was provided for holding the tail of the shirt in position during the pressing operation. In such prior machines, the attachment or device for holding the tail of the shirt in position has been complicated and expensive and it was not easy or convenient to operate.

Likewise when said device was moved to the inoperative position, it interfered with easy access to the machine.

According to the invention, I provide an extremely simple and convenient attachment for this purpose.

Fig. 1 illustrates some of the essential parts of a pressing machine of well-known construction. This machine has a buck 1, and a head 2 which can be moved towards said buck so as to press the shirt or other garment. Said head 2 is provided with the usual handle 3.

As shown in Fig. 3, the head 2 is connected to the usual pivoted frame 4. The head 2 may be

hollow and it may be heated by steam in the usual manner. These well-known details are not illustrated in the drawings, as they form no part of the invention.

The buck 1 is mounted upon a suitable table T, having an upstanding wall W adjacent the rear edge of the table.

Fig. 1 also shows the shirt S in position on the buck 1 and ready for the pressing operation. Brackets 6 are connected to the underside of the table T, adjacent the front edge and adjacent the rear edge of said table T. Said brackets 6 are located inwardly of said edges of the table.

A loop which comprises arms 7 and 7a and a thin top strap 8, is pivotally connected to the brackets 6. For this purpose the arms 7 and 7a are connected to the brackets 6 by means of a shaft 9 which is turnably mounted in suitable bearings which are provided in the brackets 6. The arms 7 and 7a and the shaft 9 therefore turn in unison.

The arms 7 and 7a are connected to the shaft 9 in any suitable manner.

As shown in Fig. 3, the arm 7a has a substantially angular shape, and the arm 7 is provided with upstanding top and bottom portions and with an intermediate inclined portion. The strap 8 may be made by bending a thin flat strap of metal into suitable shape, and it is connected to the tops of the arms 7 and 7a by fastening members 10 which may be rivets or removable screws or the like.

In Fig. 1, the operative position of the arm 7 is shown in full lines. The free or inoperative position of the arm 7 is shown in broken lines, and in said free or inoperative position, a stop member 11 abuts the underside of the table T. The arms 7 and 7a can be made of any suitable metal, and they may be respectively provided with hollow bosses 12 and 12a as shown in Fig. 3. Set screws 14 connect said bosses to the shaft 9, which extends through said bosses.

The boss 12a has an integral lug to which the stop member 11 is suitably connected. The lower upstanding part of arm 7 is in front of the front edge of the table T and the upstanding part of arm 7a is behind the rear edge of the table T. Hence the operator can conveniently move the arms in unison by manipulating the front arm 7.

In the inoperative position, the arms 7 and 7a and the strap 8 completely clear the buck 1, and said arms and the strap 8 are held spaced in an endwise direction (as shown in broken lines in Fig. 1) from the buck 1, so that the tail of the

shirt can be conveniently placed in position on said buck. The buck is then entirely free.

Referring to Fig. 3, the table T is provided with the usual wall W along the rear edge thereof and the arms 7 and 7a are of sufficient height so that the strap 8 clears said wall when it is moved to its operative position from the inoperative position.

Said strap 8 has an arcuate shape, as shown in Fig. 3, so that it conforms to the transverse shape of the buck.

It would not be departing from the invention if the holding member 8 and the arms 7 and 7a were integral. It will be noted that the device eliminates the use of springs because the centers of gravity of the arms 7 and 7a are located above the table T, and below the buck 1, in the positions of said arms which correspond to the positions of arm 7, indicated in Fig. 1.

I have shown a preferred embodiment of my invention, but it is clear that numerous changes and omissions can be made without departing from its spirit.

I claim:

1. A pressing machine having a table and a buck located above said table and a device for holding the tail-portion of a garment on said buck, said device comprising a front arm and a rear arm and a transverse holding-member which is connected to the upper portions of said arms, brackets connected to the underside of said table, a shaft mounted turnably in said brackets, said

arms being secured to said shaft so that said arms are turnable in unison with said shaft, the lower portions of said arms being spaced outwardly from the adjacent edges of the table, the upper portions of said arms being bent inwardly over said table, said arms being turnable to a first position in which arms and said holding-member are spaced in an endwise direction from said buck so that the buck is entirely free, said arms being also turnable to a second position in which said holding-member overlies said buck and said holding-member can hold said tail-portion on said buck, stop-means constructed and located to maintain said holding-member above said table in the first position of said arms.

2. A pressing machine having a table and a buck located above said table and a device for holding the tail-portion of a garment on said buck, said device comprising a front arm and a rear arm and a transverse holding-member which is connected to the upper portions of said arms, means constructed to pivotally connect said arms to the table below said buck, said arms being turnable to a first position in which said arms and said holding-member are spaced in an endwise direction from said buck so that the buck is entirely free, said arms being also turnable to a second position in which said holding-member overlies said buck and said holding-member can hold said tail-portion on said buck.

HYMAN ELIAS COHEN. 30
